UNITED STATES PATENT OFFICE

2,087,173

STOCK WATERER

Allen R. Uden, Sheldon, Iowa

Application January 31, 1936, Serial No. 61,821

1 Claim. (Cl. 137—68)

This invention appertains to new and useful improvements in the general art of animal husbandry and more particularly to a novel stock waterer.

The principal object of the present invention is to provide a waterer which is adapted for use both in summer and winter and which in operation will be substantially foolproof.

Another important object of the invention is to provide a stock waterer which is substantially automatic in operation, always maintaining a predetermined level of water available for live stock.

Other important objects and advantages of the invention will become apparent to the reader of the following specification.

In the drawings:

Figure 1 represents a vertical sectional view through the apparatus on line 1—1 of Fig. 2.

Figure 2 represents a vertical sectional view taken substantially on line 2—2 of Figure 1.

Figure 3 is a horizontal sectional view taken substantially on line 3—3 of Figure 1.

Figure 4 is a horizontal sectional view taken substantially on line 4—4 of Figure 1.

Figure 5 is a horizontal sectional view taken substantially on line 5—5 of Figure 1.

Referring to the drawings wherein like numerals designate like parts, it can be seen that numeral 5 represents a substantially large tank embedded in the ground denoted by numeral 6. The tank 5 is provided with an upstanding neck portion 7 and around this is the spaced wall 8. This wall 8 converges as at 9 to meet the upper end of the neck 7 and in the space between the neck 7 and the wall 8 is placed sawdust or some other suitable insulating material 10.

The tank 5 is provided with a partition 11 therein terminating at its lower end in spaced relation to the bottom of the tank 5 and a reduced extension 12 extends upwardly through the neck 7, to divide the neck 7 into the water well 13 and the float chamber 14. The partition extension 12 extends upwardly above the top of the neck 7 and forms at this end portion one wall of the short tower 15 in which the float 16 normally operates. The partition 11 in the tank 5 divides the interior of the tank into the oil compartment 17 and the water compartment 18. As the oil will float on the water in the compartment 17, the oil will not enter the compartment 18, but will serve to lubricate all working parts in

the compartment 17. The top of the tower 15 is provided with a removable cap 19 whereby access can be gained to the float 16.

Hingedly connected as at 20 to the partition extension 12 is the closure 21 which at its free edge portion extends a substantial distance as at 22 beyond the adjacent edge portion of the neck 7. This closure can be lifted by the animal when he is ready to drink.

Numerical 23 represents the water supply pipe which extends into the chamber 17. The conduit extends upwardly as at 24 in the chamber 17 and then horizontally as at 25. The horizontal portion 25 has a valve 26 therein operable by the arm 27. An elongated connection rod 28 extends from the arm 27 and extends through the float 16. A wing nut 29 on the upper end of the rod 28 serves to affix the float in place on the rod 28. This horizontal portion 25 extends through the partition 11 to enter the compartment 18 as at 30.

It can now be seen, that as the live stock drink water out of the well 13, the water in the well 13 will rise and the oil in the compartment 17 will lower, thus allowing the float 16 to settle and drop the arm 27 so as to open the valve 26 and allow water to enter the compartment 18. Thus the water supply to the tank is replenished from time to time.

While the foregoing specification sets forth the invention in specific terms, it is to be understood that numerous changes in the shape, size and materials may be resorted to without departing from the spirit or scope of the invention as claimed hereinafter.

Having described the invention, what is claimed as new:

In a stock waterer, a tank, a vertically disposed partition dividing the tank into a float compartment and a discharge compartment and terminating in spaced relation to the bottom of said tank, a water supply pipe extending across the float compartment and terminating at its discharge end in the discharge compartment, a valve in that portion of said pipe in said float compartment and having an operating arm, a float in said float compartment, a rod connection between the float and said arm, and an oil column in said float compartment supporting said float and extending downwardly to a level between the lower edge of the partition and the valve to lubricate the valve.

ALLEN R. UDEN.
